UNITED STATES PATENT OFFICE.

GEORGE P. ABORN, OF BROOKLINE, MASSACHUSETTS, ASSIGNOR TO THE BLAKE & KNOWLES STEAM PUMP WORKS, A CORPORATION OF NEW JERSEY.

ENGINE-VALVE.

1,102,181.

Specification of Letters Patent. Patented June 30, 1914.

Application filed November 6, 1912. Serial No. 729,739.

To all whom it may concern:

Be it known that I, GEORGE P. ABORN, a citizen of the United States, residing at Brookline, county of Norfolk and State of Massachusetts, have invented certain new and useful Improvements in Engine-Valves, fully described and represented in the following specification and the accompanying drawings, forming a part of the same.

10 This invention relates to steam engines and pumps equipped with fluid actuated valves.

The object of the invention is to provide a simple and compact valve mechanism for working the steam expansively; and, when used in steam pumps, to slow down the piston stroke near its end to allow the valves in the pump cylinder to seat quietly and with little shock, and to secure an easy reversal of the piston stroke.

In the drawings, Figure 1 is a section longitudinally of the steam cylinder and on the line of the valve rod. Fig. 2 is a section transverse to the cylinder. Fig. 3 is a sectional plan of the auxiliary cylinder and valve yoke, taken on the line 3—3 of Fig. 1, and Fig. 4 is a plan view of the valve seat on the steam cylinder showing port connections.

30 The main cylinder is indicated at 10, and in Fig. 1, the main piston is partly shown at 11. The main valve seat 12, as shown in Figs. 1 and 4, is equipped with three main ports, 13 and 14 being the inlet channels and 15 the exhaust. The main slide valve 16 is moved in part by the valve rod 22 and in part by the auxiliary piston 17 inclosed in the auxiliary steam cylinder 18. The cylinder 18 is in axial parallelism with the main cylinder which it surmounts, but this arrangement, though preferred in the present instance, is not essential to the carrying out of the invention. The valve rod 22 carries a yoke 21 to which are attached an auxiliary valve 19 on one side of the yoke, and a cut-off valve 20 on the other side of the yoke. The auxiliary valve controls the admission of steam to the auxiliary cylinder; the cut-off valve controls the admission of steam to the main steam valve. The main valve is formed with a vertical lug which engages a recess in the auxiliary piston so that the valve and auxiliary piston move together. This lug passes through the valve yoke 21, as best shown in Fig. 3, the dimensions be-

ing such that there is lost motion between the yoke and the main valve.

As shown in Fig. 4, the main valve seat is equipped with five ports; cut-off ports 25 and 26 and ports 13, 14 and 15 previously described. The openings 37 and 38 are for the admission of steam into the auxiliary steam chest.

The described mechanism operates as follows: Steam enters at opening 40 and passes into the auxiliary chest through passages 37 and 38. Assuming the auxiliary piston 17, as viewed in Fig. 1, to be in its extreme left-hand position, being so held by steam admitted to the right of the piston by ports 29 and 33 as shown in Fig. 3; the main valve 16 will also be in a similar position and will allow steam to pass through ports 28 and 25 to cavity 36 in main valve 16, then through port 14 into main cylinder 10, causing the piston 11 to move to the left. At the same time steam will exhaust through port 13, port 15, and exhaust outlet 41. At a predetermined point in the travel of the main piston 11, the usual tappet gear (not shown) will move the valve rod 22 to the right. The valve rod will carry with it the yoke 21, the auxiliary valve 19 and the cut-off valve 20. The movement of the auxiliary valve 19 to the right first uncovers port 27 (Fig. 3) and closes exhaust port 28, admitting steam at the left of auxiliary piston 17 through port 35 which balances the piston, as ports 29 and 33 at the opposite end are still open to the steam pressure. The continued movement of the yoke 21 carries the cut-off valve 20 over the port 23, thus cutting off the supply of steam to the main steam valve, the stroke of the main steam piston being completed by expansion of the steam previously admitted to the cylinder. When the lost motion between the valve yoke and the main steam valve is taken up, the main valve is also moved to the right until just before it reaches its central position, at which point the auxiliary valve 19 will have moved far enough to have opened port 30 to exhaust and closed port 29 to steam. The auxiliary piston is thereby thrown out of balance and is driven over to the right until it cushions on the steam confined between its end and the cylinder head due to the covering of exhaust port 32 by the piston. The main valve will now be in a position for the return stroke of the main

2
piston 11. When it is desired to have the steam follow full stroke, as in warming up, either one or both of the bleeder valves 42, 43 covering the ports 44 and 45 may be opened. These valves admit steam through ports 44 and 45 to the main slide valve through which it may pass into the main cylinder independently of the cut-off arrangement.

10 The construction as thus shown and described is the preferred embodiment of the invention; but it will be understood that the invention is not limited to the specific arrangement of parts illustrated, but that 15 the broader features of the invention, as defined by the claims, may be embodied in other constructions.

What is claimed is:—

1. In combination, a main slide valve, 20 fluid actuated means adapted partially to control said valve, an auxiliary valve controlling the fluid actuated means, a cut-off valve, and a valve rod moving the main slide valve, the auxiliary valve and the cut-off valve.

2. In combination, a main slide valve, fluid actuated means and a valve rod operating jointly to control the said slide valve, auxiliary ports in communication with the fluid 30 actuated means, cut-off ports in communication with the main slide valve, and a valve mechanism operated by the said valve rod to control the said auxiliary and cut-off ports.

3. In combination, a main slide valve, fluid actuated means and a valve rod to move said valve, an auxiliary valve controlling the movement of the fluid actuated means, a cut-off valve adapted to limit the 40 supply of fluid to the main slide valve, the said valve rod controlling the movements of the said auxiliary and cut-off valves.

4. In combination, a main cylinder, a main slide valve, a valve rod, an auxiliary cylinder, an auxiliary piston located within the 45 auxiliary cylinder, the said piston and said valve rod operating jointly to control the main slide valve, a cut-off valve adapted to control the movement of fluid to the main 50 slide valve, and means to pass the fluid to the main slide valve independently of the said cut-off valve.

5. In combination, a main slide valve,

fluid actuated means and a valve rod to move the said valve, a second valve device 55 equipped with ports to control the said fluid actuated means and with ports to limit the supply of fluid to the main slide valve, the said second valve device being located between the said main slide valve and the fluid 60 actuated means.

6. In combination, a fluid actuated valve gear including an auxiliary cylinder and an auxiliary piston, a valve rod, a main slide valve attached to said piston and moved by the piston and by the valve rod, and a valve device combining auxiliary and cut-off ports and mounted above the main slide valve and below the said piston and movable independently of said piston. 70

7. In combination, a main slide valve, fluid actuated means and a valve rod operating jointly to move said valve, a second valve device equipped with ports to control the said fluid actuated means and with 75 ports to limit the supply of fluid to the main slide valve, and means to supply fluid to the main slide valve independently of said limiting ports.

8. In combination, the main valve, a piston connected with the said valve to move it, a cylinder in which said piston is located, an auxiliary valve and a cut-off valve both interposed between said cylinder and the seat for the main valve, the auxiliary 85 valve controlling the passage of fluid in the said cylinder and the cut-off valve controlling the supply of fluid to the said main valve, a carrier for the said auxiliary and cut-off valves having an opening through 90 which the stem of the main valve is extended, and a valve rod attached to the carrier.

9. In combination, the main slide valve 16, attached to auxiliary piston 17, the valve yoke 21 equipped with valves 19 and 20 95 and adapted to move the main valve 16 intermittently, substantially as shown and described.

In testimony whereof, I have hereunto set my hand, in the presence of two subscribing 10 witnesses.

GEORGE P. ABORN.
